UNITED STATES PATENT OFFICE.

ELI POLLAK, OF PHILADELPHIA, PENNSYLVANIA.

OIL-BURNER.

SPECIFICATION forming part of Letters Patent No. 735,292, dated August 4, 1903.

Application filed May 17, 1902. Serial No. 107,785. (No model.)

To all whom it may concern:

Be it known that I, ELI POLLAK, a citizen of the United States, residing at Philadelphia, in the county of Philadelphia and State of Pennsylvania, have invented a new and useful Wickless Oil-Burner, of which the following is a specification.

This invention relates generally to lamps, and more particularly to a wickless hydrocarbon-lamp; and the object of the invention is to provide a simple and efficient lamp of this character which can be utilized in connection with an oil or an incandescent lamp or it can be utilized as a brazing or heating torch.

Another object of the invention is to provide a simple and efficient construction of vaporizing-burner in which the hydrocarbon fluid will be thoroughly vaporized and 20 mingled with air, thereby producing perfect combustion and avoiding all smoke and smell.

With these objects in view the invention consists in the novel features of construction and combination, all of which will be fully 25 described hereinafter and pointed out in the claims.

In the drawings forming part of this specification, Figure 1 is a perspective view of a lamp constructed in accordance with my invention, the chimney and mantle being shown upon the burner. Fig. 2 is a top plan view of the burner, the retort-vaporizer, and the air mixer or commingler. Fig. 3 is a vertical sectional view taken through the reservoir 35 and burner, the retort-vaporizer being shown in elevation. Fig. 4 is a detail view showing one side of the retort, said view being partly in elevation and partly in section. Fig. 5 is an enlarged detail view of the air-mixer.

In carrying out my invention I employ a reservoir A, which may be of any suitable or desirable pattern and is provided with an air-inlet tube A', to which any suitable form 40 of air-forcing apparatus may be connected.

B indicates a pipe which extends into the reservoir to a point adjacent to the bottom, the upper end of said pipe being connected to the coupling B', in which operates a needle-valve B² for the purpose of controlling 45 the flow of hydrocarbon from the pipe B to the pipe C, which is also connected to the

coupling B' and which is connected at its upper end to a retort D, which is essentially in the form of a drum. A flash-pan E is provided beneath this retort, said pan being 55 preferably supported by means of a bracket connected to the pipe C.

The burner comprises an essentially cylindrical-shaped casing F, which is supported upon the standard F', extending upwardly 60 from the center of the top of the reservoir. The casing F is open at the side adjacent to the retort and is also open at the top. A perforated metal plate G is secured upon the open end of the casing F adjacent to the retort, said perforated plate being held in place by means of the threaded collar G', and at the open top of the casing a wire screen H is secured by means of a ring or collar H'. The casing F is formed with a threaded neck F², 70 into which screws the pipe-section I, the air-mixer K being attached to the outer end of said pipe-section, said mixer being essentially in the form of a hemisphere and provided with a series of perforations K', through which 75 the air can enter. A valve-casing L is connected to the outer end of the air-mixer K, and in which operates the needle-valve L', by means of which the flow of vapor into the mixer and burner is regulated, said vapor being conducted from the retort D to the valve-casing L by means of a pipe M. The casing F has a central threaded stud N projecting upwardly from the bottom thereof, and secured upon said stud is a solid metallic body 85 O, the purpose of which is to cause a considerable circulation within the casing, thereby producing a complete commingling of the vapor and air before passing through the wire screen for combustion, and by producing this 90 complete commingling of vapor and air I am enabled to provide almost perfect combustion, and thereby reduce smoke and smell to a minimum.

In operation the reservoir is filled with oil 95 to any desired extent and a definite amount of air compressed within the same. The needle-valve B² is then partially opened, permitting a small quantity of hydrocarbon fluid to pass upwardly into the retort, and a 100 small quantity of alcohol or other combustible fluid is ignited in the flash-pan E, there-

by heating the hydrocarbon fluid contained within the drum-shaped retort and vaporizing the same. The vapor then passes from the retort through the pipe M, valve-casing 5 L, and through the air-mixer K, pipe I, into casing F, and while the vapor is so passing a definite quantity of air is being drawn in through the mixer and mixes with the vapor. The commingling vapor and air becomes 10 thoroughly mixed in the casing F, and inasmuch as the flash-pan is still burning a portion of the commingled air and vapor will be ignited at the perforated plate G and will continue to burn at that point, thereby continuing 15 to heat the drum-shaped retort, and thereby complete the vaporization of the fluid. The major portion of the vapor will pass upwardly through the screen and burn above the said screen, the solid body O serving to 20 cause a sufficient circulation prior to combustion to provide for a thorough commingling of the vapor and air. The retort is provided with suitable valves to prevent back pressure.

25 By the construction herein shown and described I produce a lamp in which hydrocarbon oils of every description are thoroughly vaporized prior to being mixed with air, and the fluid so vaporized is thoroughly commingled with the air prior to combustion, thereby reducing smoke and smell incidental to combustion to a minimum.

In the drawings hereto annexed and forming part of this specification I have shown 30 what I consider the best means for carrying out my invention; but I do not wish to limit myself to the exact details of construction, as it is obvious that they may be changed or altered without departing from the broad 35 principles of my invention. It will also be understood that I do not limit myself to the exact construction and arrangement of drum-retort, but may employ any suitable construction for carrying out the vaporization of the 40 fluid fuel.

45 Having thus fully described my invention,

what I claim as new, and desire to secure by Letters Patent, is—

1. In a device of the kind described, the combination with a burner perforated on one side, of a retort arranged adjacent said perforated side, a metal body within the burner and projecting upward from the bottom of same, an air-mixer connected to the opposite side of the burner and a pipe leading 55 around the burner from the retort to the air-mixer.

2. The combination with a cylindrical casing perforated on one side, an upwardly-extending metal body centrally arranged on the 60 bottom of the casing, of a gauze top, a retort adjacent the perforated side, an air-mixer chamber on the opposite side of the casing, a pipe exterior of the casing connecting the retort and mixing-chamber, and a valve adapted 65 to regulate the passage of vapor to the mixing-chamber.

3. The combination with a reservoir, of a threaded socket on the top of the reservoir, an upwardly-open, cylindrical burner-casing 70 having flanged openings on opposite sides, an integral projection extending downward from the bottom of the casing, and having a downwardly-open, threaded socket therein, a standard threaded into the said sockets and 75 adapted to support the casing, a pipe secured in one of the side openings of the casing, a mixing-chamber carried by said pipe, a perforated plate secured in the openings in the opposite side of the casing, a gauze disk over 80 the top of the casing, a flanged ring secured around the top of the casing and adapted to retain the gauze in position, a retort adjacent the perforated plate, means for feeding oil to the retort and burner-casing, and an 85 upwardly-projecting metal body arranged within the casing.

ELI POLLAK.
